(57) **CLAIM**

The ornamental design for a bell mug, as shown and described.

DESCRIPTION

FIG. 1 is a front, right isometric perspective view of a bell mug showing my new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof.

FIG. 7 is a bottom plan view thereof.

FIG. 8 is a front, right isometric perspective view of a second embodiment of the bell mug showing my new design, with the lid shown in phantom lines.

FIG. 9 is a front elevational view of the mug of FIG. 8.

FIG. 10 is a rear elevational view of the mug of FIG. 8.

FIG. 11 is a right side elevational view of the mug of FIG. 8.

FIG. 12 is a left side elevational view of the mug of FIG. 8.

FIG. 13 is a top plan view of the mug of FIG. 8.

FIG. 14 is a bottom plan view of the mug of FIG. 8.

FIG. 15 is front, right isometric perspective view of a third embodiment of the bell mug showing my new design, with the handle shown in phantom lines and an alternate lid design.

FIG. 16 is a front elevational view of the mug of FIG. 15.

FIG. 17 is a rear elevational view of the mug of FIG. 15.

FIG. 18 is a right side elevational view of the mug of FIG. 15.

FIG. 19 is a left side elevational view of the mug of FIG. 15.

FIG. 20 is a top plan view of the mug of FIG. 15.

FIG. 21 is a bottom plan view of the mug of FIG. 15.

FIG. 22 is a front, right isometric perspective view of a fourth embodiment of the bell mug showing my new design, without handle and without lid.

FIG. 23 is a front elevational view of the mug of FIG. 22, the rear elevational view being a mirror image thereof.

FIG. 24 is a right side elevational view of the mug of FIG. 22, the left side elevational view being a mirror image thereof.

FIG. 25 is a top plan view of the mug of FIG. 22; and, FIG. 26 is a bottom plan view of the mug of FIG. 22.

The broken lines in the figures are for illustrative purposes only and form no part of the claimed design.
